UNITED STATES PATENT OFFICE.

WILLIAM DUECKER, OF MEMPHIS, TENNESSEE.

BELT.

1,203,859.

Specification of Letters Patent.

Patented Nov. 7, 1916.

Application filed November 19, 1914. Serial No. 873,053.

To all whom it may concern:

Be it known that I, WILLIAM DUECKER, a citizen of the United States, residing at Memphis, in the county of Shelby and State of Tennessee, have invented a new and useful Belt, of which the following is a specification.

The device forming the subject matter of this application is a driving belt, and one 10 object of the invention is to provide a belt of this sort having a novel form of facing.

The invention aims to provide a driving belt which will not stretch and to provide a belt the "constituent elements of which 15 will not separate.

It is within the province of the invention to provide a belt which may be rendered water proof in a novel manner.

The invention contemplates the construction whereby no raw edges will be left upon the facing which is applied to the body portion of the belt.

It is within the scope of the invention to improve generally and to enhance the utility 25 of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 the scope of what is claimed without departing from the spirit of the invention.

In the accompanying drawings:—Figure 1 shows in cross section a belt embodying the present invention; Fig. 2 is an elevation 40 showing one longitudinal edge of the belt.

In the drawings, a textile facing is shown at 8 and is turned in as indicated at 9. Located within the facing is a core 10 to which the facing is secured by means of cement 45 indicated at 11. The facing is elongated in

a stretcher, as hereinbefore described, and while in a stretched condition, the exterior of the facing 8 is coated with cement indicated at 12. By means of cement shown at 14, the facing 8 is attached to the working 50 surface of a leather belt body 15.

The facing is co-extensive in length and width with the respective leather body. Further, since the edges of the textile body are turned in, as shown at 9, there are no raw 55 or ragged edges adjacent the lateral edges of the belt.

As shown in Fig. 2, the ends of the body portion of the belt are beveled and its beveled ends are overlapped and cemented together as shown at 19. The ends of the facing 8 are beveled, overlapped and cemented as shown at 20, the overlapped portions 19 and 20 of the body and the facing respectively being located out of alinement with 65 each other.

Having thus described the invention, what is claimed is:—

A driving belt comprising a leather body; a textile facing the longitudinal edges of 70 which are folded inwardly toward each other in opposite directions and are located in a common plane, the inwardly folded edges of the facing being secured to the body, and the body being of substantially 75 the same width as the facing; and a core within the facing and substantially filling the same; the ends of the body being beveled and overlapped and the ends of the facing and the core being beveled and overlapped, 80 the bevels of the body on the one hand and of the facing and the core upon the other hand being inclined in opposite directions.

In testimony that I claim the foregoing as my own, I have hereto affixed my signature in the presence of two witnesses.

WILLIAM DUECKER.
